Primary Examiner — Lauren R Calve(57) **CLAIM**

The ornamental design for a clothes rack, as shown and described.

DESCRIPTION

FIG. 1 is a perspective view showing the new design for a clothes rack in a first position;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rear view thereof;

FIG. 8 is a perspective view showing the new design for a clothes rack in a second position;

FIG. 9 is a front view thereof;

FIG. 10 is a right side view thereof;

FIG. 11 is a left side view thereof;

FIG. 12 is a top view thereof;

FIG. 13 is a bottom view thereof; and,

FIG. 14 is a rear view thereof.

The portions of the clothes rack depicted in broken lines in FIGS. 1-14 form no part of the claimed design.

1 Claim, 6 Drawing Sheets(56)
